MICROMETER GAUGES

Charles Zelnick, Saginaw, Mich., assignor to The Lufkin Rule Company, Saginaw, Mich.

Application November 23, 1953, Serial No. 393,781

7 Claims. (Cl. 33—164)

This invention relates to micrometer gauges in general, and more particularly to a novel and improved stop means which is actuated to feed the spindle into engagement with the work, and which automatically ceases feeding the spindle and simply revolves when the spindle and anvil are properly engaging the work so that the measurement can be read.

As is well known, the "feel" associated with the use of micrometers or similar measuring devices, or the point at which the user "feels" the work is properly engaged by the device and that reading should be taken, varies with the individual, unless he takes a large number of readings per day. Consequently, there are often inaccuracies in the readings because the spindle and anvil are engaging the "work" with either too much or too little pressure when the readings are taken, relative to the engaging pressure at which the device was calibrated.

One of the prime objects of my invention is to provide means associated with the spindle of a gauge, which can be actuated to feed the spindle to the work until the work is engaged with a predetermined pressure, whence rotation of the spindle will cease, regardless of the continued action of said means, thus eliminating the necessity of relying on the "feel" of the individual using the device, and insuring uniformity and accuracy of measurement.

A further object of the invention is to design means for rotating the spindle which ceases feeding the spindle when a predetermined measuring pressure is attained, thereby preventing the overfeeding of the spindle with consequent wear and/or damage to the work-contacting surfaces of the micrometer.

Another object of the invention is to design means for feeding the spindle of a micrometer to the "work" and which ceases rotating the spindle when the spindle is locked in engagement with said work, thus providing a gauge which remains in adjusted position until a reading can be taken.

With the above and other objects in view, the present invention consists in the combination and arrangement of parts, hereinafter more fully described, illustrated in the accompanying drawing, and more particularly pointed out in the appended claims, it being understood that changes may be made in the form, size, proportion and minor details of construction, without departing from the spirit, or sacrificing any of the advantages of the invention.

In the drawing:

Fig. 1 is a side elevational view of a micrometer showing my improved actuating collar thereon.

Fig. 2 is a part sectional, side elevational view of the clamping member and actuating collar mounted on the end of the micrometer sleeve.

Fig. 3 is a part sectional, side elevational view of the actuating collar only.

Fig. 4 is a transverse sectional view taken on the line 4—4 of Fig. 2.

2

Referring now more particularly to the accompanying drawing wherein I have shown a micrometer of the general design illustrated and described in Patent No. 2,212,910 with my improved mechanism incorporated therein, the micrometer includes a frame 10 provided with an anvil 11, and a tubular barrel 12 inscribed with a longitudinal scale 13 projects from the frame 10 and is interiorly threaded at its outer end to receive the threaded outer end of a spindle 14 as usual.

10 A tubular sleeve 15 is telescoped over the inscribed barrel 12, the outer end of said sleeve being internally threaded as shown to receive the threaded end (not shown) of the spindle 14, which projects beyond the barrel 12. The outer end portion of the sleeve 15 is knurled as at 16, and the opposite end is beveled and bears a circumferential scale 17 which cooperates with the longitudinal scale 13 in the conventional manner.

15 Formed on the extreme end of the sleeve 15 is a secured or split portion 18 of reduced diameter, including a threaded portion 19, and a tapered nose portion 20. A clamping member 21 includes a reduced outer threaded end 22 and a knurled cap 23 is mounted thereon and is interiorly threaded as at 24, the member 21 being bored with a cooperating taper as at 25 to accommodate the nose portion 20 and clamp the split outer end of the sleeve 15 on the projecting threaded end of the spindle 14. In this manner, the rotating sleeve 15 and clamping member 21 are clamped to the gauging spindle 14 and when actuated, serve to feed the spindle 14 into engagement with the work in the usual manner.

20 This particular structure is more specifically illustrated and described in previously-mentioned Patent No. 2,212,910, and I do not deem it necessary to describe it in greater detail. The structure dealt with to this point is common to applicant's assignee's micrometers, and it is the improvement hereinafter described to which this present application is directed.

25 The instant improvement includes a knurled collar 26 seated on a shouldered portion 27 provided by reducing the diameter of the clamping member 21, a certain amount of clearance 28 being provided between the shouldered portion 27 and collar 26. Formed in the portion 27 is an annular groove 29 in which is seated a friction coil spring 30 having only a few convolutions, the one end of the spring being bent radially inwardly as at 31 so as to be accommodated in the radial passage 32 formed in the wall of the member 21. Thus, the friction spring 30, which is of greater diameter than the internal diameter of collar 26 and exerts a uniform pressure against the internal wall of the collar 26 over the length of the spring opposes relative rotation of the collar 26 and member 21 is anchored in position and cannot become disengaged.

30 The cap end 23, of course, serves to prevent the collar 26 from slipping off the end of the clamping member 21, and is readily disengageable to allow removal of the collar 26 to replace the spring 30 after prolonged use or for any other purpose.

35 In practice, the collar 26 is grasped between the thumb and forefinger and rotated or twirled to feed the spindle 14 into engagement with the work to be measured. When a predetermined setting is attained, the knurled collar 26 will overcome the opposition of the spring 30 and rotate relative to the clamping member 21 instead of further feeding the spindle 14 into the work. At this point, the user must exercise considerably more force to revolve the collar 26 and is then aware that the spindle is locked in measuring position, and that the gauge is ready to be read. The user is thus prevented from inadvertently further actuating the spindle 14 and possibly damaging the gauge measuring surfaces and work, and taking an inac-

curate reading. Because the spring is annular or is generally annular in the sense that it has a curvilinear surface contacting the internal surface of collar 26, only a fine peripheral portion of the wire spring engages the collar and there is little possibility of grit getting in between the spring and wall and clogging the action. Any dirt which might accumulate over a long period of use is easily dislodged by moving the cap assembly through a proper cleaning solvent.

It will thus be seen that I have perfected a very simple and improved automatic stop means for protecting the "work" and the gauge contact surfaces from undue clamping strains, and for locking the gauge at the same setting whenever it is used, thus insuring greater accuracy of measurement. Further, the friction spring pawl of the instant device is so anchored that it cannot be pulled loose and thus render the stop mechanism inoperative.

It is obvious that the instant means also assures that the tubular sleeve 15 can be set at the true zero when the spindle is brought into engagement with the anvil to calibrate the gauge as determined by the point at which the knurled collar 26 begins to rotate relative to the clamping member 21.

From the foregoing description, it will be apparent that I have perfected a very simple, practical and inexpensive automatic stop means for micrometer gauges and the like.

What I claim is:

1. In a micrometer gauge, the combination with the measuring spindle and the split end sleeve therefor, of an annular tubular clamping member for clamping the split end of the actuating sleeve on the measuring spindle, said clamping member having an annular groove therein, an actuating collar freely revolvable on said clamping member, and an annular friction spring comprising a wire of annular cross section wound in side by side convolutions of greater diameter than the diameter of said collar so as to exert a pressure thereagainst disposed in said groove to maintain said collar and clamping member in rotative, frictional engagement in the absence of counteractive endwise pressure on the spindle opposing rotation thereof.

2. In a micrometer gauge the combination with the measuring spindle thereof and an annular member normally clamped thereon, of an actuating collar having an internal diameter greater than the diameter of said member, an annular friction spring comprising a wire of substantially annular cross section wound in side by side convolutions of greater diameter than the internal diameter of said collar, said convolutions being of equal diameter and exerting a uniform pressure against the internal wall of the actuating collar over the length of the spring, and means for preventing endwise movement of said spring when the collar is twisted and has relative rotation with said member because of a counteractive endwise pressure on the spindle opposing further rotation thereof.

3. The combination defined in claim 2 in which one end of said spring is bent radially inwardly and a radial passage is provided in the wall of said member to receive said end and secure said spring.

4. In a micrometer gauge or the like; the combination with the relatively rotatable and axially adjustable barrel and spindle assembly thereof, of an actuating collar, mounted on a surface of one of said barrel and spindle assembly, having an internal diameter greater than the diameter of said surface; a generally annular friction

spring comprising a wire of generally annular cross section wound in side by side convolutions of greater diameter than the internal diameter of said collar, said convolutions exerting a pressure against the internal wall of the actuating collar over substantially the length of the spring; and means for preventing endwise movement of said spring when the collar is twisted and has relative rotation with said surface because of a counteractive endwise pressure on the said one of the spindle assembly and barrel on which said collar is mounted opposing further rotation thereof.

5. In a micrometer gauge or the like; the combination with the relatively rotatable and axially adjustable barrel and spindle assembly thereof; of an actuating collar, mounted on a surface of one of said barrel and spindle assembly, having an internal diameter greater than the diameter of said surface; a generally annular friction spring comprising a wire wound in side by side convolutions of greater external diameter than the internal diameter of said collar, said convolutions exerting a pressure against the internal wall of the actuating collar over substantially the length of the spring; and means for preventing endwise movement of said spring when the collar is twisted and has relative rotation with said member because of a counteractive endwise pressure on the said one of the spindle assembly and barrel on which said collar is mounted opposing further rotation thereof.

6. In a micrometer gauge or the like; the combination with the relatively rotatable and axially adjustable barrel and measuring spindle assembly thereof; of an actuating collar mounted on an exposed annular surface of said spindle assembly having an internal diameter greater than the diameter of said member; an annular friction spring comprising a wire wound in side by side convolutions of greater diameter than the internal diameter of said collar; said convolutions being of substantially equal diameter and exerting a pressure against the internal wall of the actuating collar over substantially the length of the spring, and means for preventing endwise movement of said spring when the collar is twisted and has relative rotation with said member because of a counteractive endwise pressure on the spindle assembly opposing further rotation thereof.

7. In a micrometer gauge or the like; the combination with the relatively rotatable and axially adjustable barrel and spindle assembly thereof; of an actuating collar, mounted on a surface of one of said barrel and spindle assembly, having an internal diameter greater than the diameter of said surface; a friction spring disposed circumferentially on the said surface and exerting a pressure against the internal wall of the actuating collar over a substantial portion of the length of the spring; and means at at least one end of said spring securing said spring to said surface to prevent its rotation with said collar when said surface cannot rotate because of a counteractive endwise pressure on the said one of the spindle assembly and barrel on which said collar is mounted opposing further rotation thereof.
